CLAIM

The ornamental design for a necklace, as shown and described.

DESCRIPTION

FIG. 1 is a front elevational view of the necklace showing my new design;

FIG. 2 is a rear view thereof;

FIG. 3 is a top view thereof;

FIG. 4 is a bottom view thereof;

FIG. 5 is a left view thereof;

FIG. 6 is a right view thereof;

FIG. 7 is a front perspective view thereof;

FIG. 8 is a back perspective view thereof;

FIG. 9 is a first enlarged view thereof;

FIG. 10 is a second enlarged view thereof;

FIG. 11 is a third enlarged view thereof;

FIG. 12 is a fourth enlarged view thereof;

FIG. 13 is a fifth enlarged view thereof;

FIG. 14 is a sixth enlarged view thereof;

FIG. 15 is a seventh enlarged view thereof; and,

FIG. 16 is an eighth enlarged view thereof.

The broken lines depict portions of the necklace that form no part of the claimed design.

1 Claim, 16 Drawing Sheets
